UNITED STATES PATENT OFFICE.

GEORGE HILLARD BENJAMIN, OF NEW YORK, N. Y.

BY-PRODUCT COKE-OVEN.

1,205,698.

Specification of Letters Patent. Patented Nov. 21, 1916.

Application filed December 11, 1911. Serial No. 664,987.

To all whom it may concern:

Be it known that I, GEORGE HILLARD BENJAMIN, a citizen of the United States, residing at New York city, in the county and State of New York, have invented certain new and useful Improvements in By-Product Coke-Ovens, of which the following is a specification.

My invention consists in an improved construction of by-product coke ovens, by reason of which more efficient and economical heating of the ovens can be obtained, with the consequent production of a more uniform grade of coke, and by-products, than has heretofore resulted.

My invention consists primarily in the means employed to obtain high temperatures in the heating flues, and secondarily in various features of construction, which will be set forth in the specification and specifically pointed out in the claims.

The accompanying drawings will serve to illustrate my invention, in which:

Figure 1 is a vertical section through the oven, supporting structure, and coke car, taken along the line I—I of Fig. 2. Fig. 2 is a horizontal section, taken along the line II—II of Fig. 1. Fig. 3 is an enlarged vertical section taken through the ovens, structure and coke car, along the line III—III of Fig. 2. Fig. 4 is a transverse section through one of the coke ovens, taken along the line IV—IV of Fig. 2. Fig. 5 is a transverse section through a series of the vertical flues, taken along the line V—V of Fig. 2. Fig. 6 is an enlarged vertical section at the bottom of one of the heating flues, showing the burner and the connections through which gas and air are introduced into the heating flues, also showing in elevation, the pivotal support for the doors which close the bottom of the heating flues, and the lock for the doors. Fig. 7 is a sectional view of the parts shown in Fig. 6, taken at right angles to such view. Fig. 8 is a longitudinal vertical section and plan, illustrating a modification of the construction shown in Fig. 3. Fig. 9 is a horizontal section and plan, taken on the line IX—IX of Fig. 8. Fig. 10 is a transverse section, taken along the line X—X of Fig. 9.

Referring to the drawings: 10 indicates a suitable framework for the support of the ovens, which may be of iron, brick, cement or other suitable material. The oven 11 is located upon the top of the framework, and

sufficiently high above the level of the ground, to permit a car 12 to be moved under the oven, on a trackway 13. The oven, as a whole, consists of the inclosing walls 14, located at the two sides and two ends of the structure, and top wall 15, which overlies the heating flues and coking chambers, to be hereafter described. On the top of the top wall 15, are mounted rails 16, over which may be moved cars 17, which serve to convey coal to be discharged into the ovens, through openings 18. The wall 15 is likewise provided, over each coking chamber, with a gas flue 19, which communicates with the gas conduit 20, on the top of the wall 15. Each of the openings 18 is provided with a cover 21, and each of the gas flues 19, with a valve 22.

In Fig. 8, additional openings 23 are provided, which communicate with the top of the heating flues and are provided with covers 24, the object of which arrangement is to provide means for cleaning the gas flues from the top of the structure.

Located within the walls 14—15, transversely and alternately disposed, are the heating flues 25, and coking chambers 26. The heating flues 25 communicate at the top with a flue 27, through which the products of combustion are conveyed to the chimneys 28. Two chimneys are shown, one at each side of the flues and located at the center of the structure. Heating flues 29, corresponding to the flues 25, are also located at opposite ends of each coking chamber 26, which flues also communicate with the flue 27.

Located at the bottom of each of the heating flues 25—29, is a gas burner 30, and connected to each gas burner, is a gas pipe or flue 31, situated on one side of the structure, and an air pipe or flue 32, situated on the other side of the structure. In the gas pipe 31, are arranged suitable valves 33 for controlling the gas fed to a group of burners, and in the air pipe 32, a valve 34 for controlling the air fed to a group of burners, and at each burner are two valves, one 35, for controlling the gas fed to a burner, and one 36, for controlling the air fed to a burner.

The main gas pipe 31 is connected to a gas pump 40, and the air pipe 32 is connected to an air pump 41, which pumps are assumed to be driven by a suitable motor, and in such manner that the gas and air are delivered under pressure at the burners. Pref-

erably the gas is delivered at a pressure of one pound to the square inch, and the air at a pressure of one and one quarter pounds to the square inch, hot or cold. The means 5 for creating these pressures, the construction of the burners, air and gas heating regenerators may all be substantially in accordance with the construction disclosed in my prior Patent No. 948,538 dated February 10 8th, 1910, or any other construction may be employed, by means of which similar results may be obtained.

I wish it understood that I do not limit myself to the pressures stated for the gas 15 and air, as these pressures may be varied. In practice, however, I have found that the best results were obtained when using semi-water gas, by maintaining the pressures of the gas and air respectively at one pound 20 and one and one quarter pounds to the square inch. Where the gas is one having a greater number of B. T. units than are contained in water gas, it is sometimes found necessary to increase the pressure of the air. When 25 using certain gases, as for instance oven gas, I have found it advisable to pre-heat the air. With gas derived from the disassociation of oil, I have found it advisable to chill the air. In practice I have found, when 30 using gas derived from the coking chambers, that it was possible to obtain a temperature of from 2700° to 3000° F. in the heating chambers. Manifestly, by decreasing the amount of gas and air introduced, 35 while maintaining the pressures, the temperature of the heating flues can be increased or decreased, as desired. In the treatment of coal for the production of coke, I have found it advisable to maintain a temperature of from 1600° to 2000°. In the treatment of coal for the production of gas, to raise the temperature to 2500°. In the treatment of peat for the production of coke, and the separation of its volatile constituents, including water and gases, to generate 40 the highest temperature possible without destruction of the furnace walls.

The gas and air fed to the burners is mixed in the burners and fed into the combustion chamber under pressure in a mixed 50 condition. Upon ignition, instantaneous combustion results, and all the heat units carried by the gas are set free and without the development of flame. In other words, 55 flameless combustion is accomplished, with a temperature development of between 3000°-4000° Fahrenheit. The theoretical considerations leading to the development of these temperatures, have been set forth, as 60 far as I have been able to do so, in my prior patent, to which I have heretofore referred.

Located at the bottom of the coking chambers 26, are doors 42, which act as closures 65 for the bottom of the chambers 26 and serve to sustain the introduced coal. Each door

42 is mounted upon a screw 43, carried in an arm 44, pivoted at 45. The arm 44 can be manipulated to close the door, by the handle 46, and the door locked by means of the bail 47, which coacts with a projection 70 on the forward end of the arm 44.

At the left of Fig. 3, the doors 42 are shown in their closed position. By reason of the shape given to the doors and to the bottom of the furnace, ingress of air into the coking chambers 26, is prevented. At the right of the figure, the door 42 is shown open and swing down to allow discharge of the coke from the bottom of the coking chamber 26 into the coke car 12. So far as 75 regards the door, its mounting, method of closing, opening, etc., I wish it understood that these are merely illustrative of a construction which may be used, and that it is not my intention to limit myself in any 80 wise to such construction as various other constructions for the purpose, will suggest themselves to engineers.

In constructing my improved ovens, I prefer that the chambers 26 shall have 90 approximately the following dimensions: Height 10 feet; length 11 feet; width from 17 to 22 inches; and that the diameter of the heating flues shall be approximately one third of that of the coking chambers, or 95 otherwise, of such diameter as to permit free combustion of the introduced gas and air. That there shall be free combustion is essential, owing to the fact that the combustion produced at the burner must be flameless 100 to produce the best results. The walls of the heating chamber may be of any suitable material; preferably, however, of a material such as carborundum brick, which will stand the high temperatures produced within the heating flues. In this connection I desire to point out that the walls of the heating flues have a material effect upon the heating value of the flame produced within the heating chambers, (which has a low radiant 110 value); that these walls serve as a medium to absorb direct heat and transmit it as radiant heat of very high temperature.

I do not limit myself to the dimensions given for the coking chambers or for the 115 heating chambers. Neither do I limit myself to coking and heating chambers arranged transversely of the structure and alternately, as I may arrange my chambers longitudinally and dispose the heating 120 chambers horizontally, as in the well known Semet Solvay furnaces. In practice, however, the best results are obtained in arranging the chambers vertically and alternately as more efficient and regular heating thereby 125 results.

In constructing the furnace I prefer that the burners 30 shall be so mounted as to be readily removable. Such a construction is provided for in Fig. 6. By removing the 130

burner 30 and the cover 24, in the construction shown in Fig. 8, access is obtained to the whole interior of the heating flues 25. Ordinarily, however, it is not necessary to obtain access to these flues, as the perfect combustion of the gas and air leaves no deposit.

It will be observed on reference to the figures, that the bottom of the heating flues 10 25 is on a level with the top of the doors 42. By reason of this construction, efficient heating of the bottom of the chambers 26 results, as the heat is a maximum at the delivery orifice of the burners owing to the instantaneou 15 combustion produced at such orifices. A further advantage in this construction is found in the fact that in the production of gas, where there is danger of disassociating the gas by high temperature, the temperature can be reduced within the heating flues in such a manner as to be high at the bottom of the heating chambers, but decreasingly of lower temperature from below upward to the exit flue 27. When the 20 burners are arranged and manipulated as above described, the coking chambers 26 act in the nature of producers and generate a large amount of gas without disassociation.

The operation of my improved coke oven 25 will be readily understood.

The door 42 having been swung into position and secured by the bail 47, is lifted up by the screw 43 until it fits tightly in the bottom of the coking chamber. This is essential, in order to prevent air from entering into the bottom of the chamber. The coal or peat to be coked is then introduced into the chamber 26 from the cars 17, through the openings 18, until the chamber 30 is full. The burners 30 are then ignited. The heat set free from the combustion in the flues 25—29, will be absorbed by the intervening walls between the flues and the coking chambers, and transmitted by radiation 35 to the body of coal or peat within the coking chamber 26, and such body of coal or peat converted into coke and various volatile products.

As previously indicated, the temperatures produced in the heating flues and transmitted, will depend largely upon the character of the material (coal or peat) introduced into the coking chambers. No explicit directions can be given as to temperatures, time required to effect results desired, etc., as these factors will depend on the character of the materials, moisture, etc., etc., all of which will be evident to those skilled in the art to which this invention belongs.

When the coking is accomplished, the bottom of the chambers is opened by dropping the doors 42 and discharging the coke into suitable cars 12, after which the doors are immediately closed, and a new charge introduced.

In the practical operation of my oven, it is found that the character of the coke produced is more uniform than in ordinary coking furnaces, (probably owing to the even distribution of heat), and that the volatile products are more readily separated and the time of coking operation reduced.

In addition to the use described, my improved oven is suitable to carry into effect many metallurgical and chemical operations which require the creation of very high temperatures, such as cannot be obtained by the direct radiation from flame, owing to the imperfect radiation of flame, but which may be successfully effected by absorbing the heat of the flame and subsequently radiating it through a medium; for instance, I may charge into the chambers 26, coal and other materials such as lime, magnesia, calcium fluorid, flue dust, breeze and the like, and bring about compounds suitable in metallurgical operations, or the production of products for use in heating or for use in metallurgical operations.

What I wish to have understood is that my improved by-product coke oven is suitable not only for separating the volatile products from coal or peat, and the production of coke, but to effect chemical reactions between coal, peat and other materials carrying volatile substances, whereby various fluids and solid products may be obtained.

Generally I wish it understood that the drawings accompanying this application are in a sense diagrammatic, and not intended to illustrate engineering features of construction, but merely general plans for construction, which may be modified in actual practice, without in anywise altering the principle of operation involved.

I wish to have it understood that I believe I am the first to have described a construction in which very high temperatures may be obtained by flameless combustion of gas and air under pressure, the absorption of such heat, and its subsequent radiation under conditions which will enhance its thermic value in producing metallurgical or chemical results.

Having thus described my invention, I claim:

1. The combination in a coking oven, of a series of coking chambers, a series of heating flues, burners located in said heating flues, said heating flues of such dimensions as to permit instantaneous combustion at the burner orifices without the development of flame, together with means for delivering gas and air to said burners at such pressures as will cause the velocity of flow to correspond to the speed of combustion.

2. The combination in a coking oven of a series of coking chambers, a series of heating flues of such size as to permit free development of flame therein, burners located

in said heating flues, together with means for delivering gas and air to said burners at pressures substantially of one to one and one quarter pounds to the square inch respectively.

5. The combination in a coking oven of a series of coking chambers, a series of heating flues, each heating flue having four lateral side walls, two of said walls constituting also the side walls of the coking chambers and an intervening space of such size as to permit free development of flame therein, burners located in said heating flues, together with means for delivering 10 gas and air to said burners at pressures substantially of one to one and one quarter pounds to the square inch respectively.

4. The combination in a coking oven of a series of coking chambers, a series of heating flues one on each side of said coking chambers, said flues consisting of four lateral side walls, two of said walls constituting also the side walls of the coking chambers, and an intervening space of such size 20 as to permit free development of flame therein, a gas burner in the bottom of each 25

of said flues, together with means for feeding gas and air to said burners at pressures substantially of one to one and one quarter pounds to the square inch respectively.

5. The combination in a coking oven of a series of coking chambers, a series of heating flues, each of these said flues having four lateral walls, two of said walls constituting also the side walls of the coking chambers and an intervening space between the walls, said walls and said space designed and adapted to permit free development of flame and evolution of the heat 30 units of said flame, a gas burner located in each flue, together with means for delivering gas and air at pressures substantially of one to one and one quarter pounds to the square inch respectively.

In testimony whereof I affix my signature in the presence of two witnesses.

GEORGE HILLARD BENJAMIN.
